UNITED STATES PATENT OFFICE.

GEORGE F. McCHEY, OF PROVIDENCE, RHODE ISLAND, ASSIGNOR TO NEW ENGLAND BUTT COMPANY, OF PROVIDENCE, RHODE ISLAND, A CORPORATION OF RHODE ISLAND.

BRAIDING-MACHINE CARRIER.

Application filed March 30, 1921. Serial No. 456,393.

To all whom it may concern:

Be it known that I, GEORGE F. McCHEY, a citizen of the United States, residing at Providence, in the county of Providence and 5 State of Rhode Island, have invented certain new and useful Improvements in Braiding-Machine Carriers, of which the following is a specification.

This invention relates to improvements in 10 yarn carriers for braiding machines, and has for its object to provide such a carrier with an improved latch or pawl for quickly controlling the feed of the yarn package while the same is being run at a very high 15 velocity.

A further object of the invention is the provision of a pawl so arranged that a movement of the pawl simultaneously effects a cooperating movement of the package 20 thereby reducing the extent of the effective operating motion of the pawl to facilitate its releasing and engaging action.

A further object of the invention is to provide a pawl upon which the yarn package 25 rests whereby the weight of the package acts upon the pawl to return it quickly into engaging position to prevent the letting off of an excessive amount of yarn even when the carrier is running at a very high speed.

30 A further object of the invention is to pivotally mount the pawl beneath the yarn package on both sides of the package spindle and to provide a stop for limiting the release motion of the pawl.

35 With these and other objects in view, the invention consists of certain novel features of construction, as will be more fully described, and particularly pointed out in the appended claims.

40 In the accompanying drawings:

Figure 1 is a side elevation partly in section illustrating my improved construction of pawl in engagement with the teeth on the yarn package and the package resting upon 45 the pawl.

Figure 2 is a view illustrating the pawl as withdrawn from the teeth on the yarn package and also as having raised the package thereon.

50 Figure 3 is a plan view on line 3-3 of Figure 1, showing the pivot supports for the pawl on opposite sides of the spindle.

Figure 4 is a detail in perspective showing my improved construction of pawl.

It is found in the construction of carriers 55 in order to run at a very high rate of speed in the usual braid-machine that the yarn let-off control-latch or pawl must be very sensitive and arranged to operate very quickly in order to prevent an excessive let-off of yarn and so reduce the ballooning or slackening of the yarn during the zigzag motion of the carrier in its serpentine raceway; and the following is a detailed description of one means by which this result may 60 be accomplished in a practical way:—

With reference to the drawings, 10 designates the base portion of a carrier on which is mounted a vertically-disposed yarn-carrying spindle 11. Near the lower end of this 70 spindle I have formed an enlargement 12, the upper or bearing face 13 of which is rounding and this enlarged portion is provided with a pair of oppositely-disposed laterally-extending pivotal trunnions 14. Extending upward from this base portion is the usual weight-carrying standard 15 on which the bottom weight 16 is slidably mounted.

A pawl or latch member 17 is provided 80 with a rounding top plate 18 having a pair of oppositely-disposed and downwardly-extending side ears 19 notched at 20 to fit over the trunnions 14 on the spindle base. On the outer end of this pawl is 85 formed a tooth or lug 25 which is adapted to fit into the teeth 23 formed in the bottom of the package 24 to control the rotation of the latter. This top plate 18 is provided with a hole 21 through which the spindle 11 90 extends. The rear end wall 22 of this hole is adapted to engage the body of the spindle 11 to limit the releasing motion of the pawl so that its tooth 25 in being withdrawn can only just clear the teeth of the yarn- 95 package to prevent lost motion in the action of the pawl. The rear end of this pawl is provided with a narrow rearwardly-extending portion 26 having a notch 27 into which the upper end 28 of the connecting wire 29 100 is looped, the upper end of this wire being looped at 30 about the weight standard 15 above the bottom weight 16.

By this construction it will be seen that

the yarn-package 24 rests directly upon the pawl and the tooth 25 of the pawl normally engages the front ratchet tooth 23 of the package to releasably hold the package from 5 rotation against tension of the leading thread 31, as illustrated in Figure 1, but when more yarn is required the tension on this thread raises the bottom-weight 16 and connector 29 to lift the rear end of the pawl 10 on its pivots 14 causing this end to raise the yarn-package and simultaneously drop the pawl tooth 25 out of engagement with the teeth of the yarn-package, by which construction it will be seen that but one-half of 15 the releasing movement of the pawl is required, as the rest of this releasing motion is obtained by raising the package. In other words the rocking of the pawl to move its toothed end downwardly, simultaneously 20 raises the package engaged by this tooth thereby dividing the extent of the releasing motion required of the pawl, which reduction of motion is also true of the return or engaging movement of the pawl, which latter 25 movement, as will be seen, is also but one-half that which would be required if it were not for the simultaneous cooperating returning movement of the package. Therefore 30 quick in its action minimizing the ballooning or slackening effect on the yarn even while the carrier is running at a very high velocity.

Then again by this construction the pawl 35 carries the weight of the yarn-package whereby when lifted to released position as illustrated in Figure 2, the weight of the package upon the pawl, has a tendency to cause the pawl to quickly return to engaging position thereby again acting upon the yarn to limit its ballooning or slackening effect 40 while the carrier is running in its usual zig-zag course about the raceway.

Another practical advantage in my im- 45 proved construction is that the pawl is pro- vided with widely-separated pivotal bearings on opposite sides of the spindle thus eliminating any possible cramping effect and by engaging the teeth on the package sub- 50 stantially on its center line, the pawl tooth will always fit squarely into the ratchet teeth.

Then again by this construction the parts may be cast and the pawl simply dropped over the spindle onto its trunnions and the 55 yarn-package set thereon. The parts of the carrier may be quickly assembled and disassembled without the use of tools.

The device is extremely simple and practical and yet inexpensive in construction and

by its use a uniform tension of the yarn is 60 obtained even while the carrier is running at a very high rate of speed.

The foregoing description is directed solely towards the construction illustrated, but I desire it to be understood that I re- 65 serve the privilege of resorting to all the mechanical changes to which the device is susceptible, the invention being defined and limited only by the terms of the appended claims.

70 I claim:

1. A carrier for braiding machines comprising a base member, a pawl mounted to rock on said member and carry the weight of the yarn package thereon, a package-engaging tooth on the pawl, and a vertically slide- 75 able yarn-tension weight mounted to freely operate between predetermined limits without affecting the movement of said pawl and to rock the pawl to simultaneously lift the package and withdraw its tooth from engagement with the package only when more 80 yarn is required.

2. A carrier for braiding machines comprising a base member, a pawl mounted to 85 rock on said member and carry the weight of the yarn package thereon, one end of said pawl being arranged to engage the package to normally hold it against rotation, a stand- 90 ard on said base, a yarn tension weight mounted to slide freely between predetermined limits on said standard, a link connected to the opposite end of said pawl and positioned in the path of movement of said weight whereby when more yarn is required 95 said weight is raised to engage said link and rock the pawl to simultaneously raise the package and also withdraw the pawl therefrom to let off more yarn.

3. A carrier comprising a base member, a 100 package spindle support, a pawl mounted to straddle said spindle and rock on said support and also carry the weight of the yarn package, a package-engaging tooth on one 105 end of said pawl, a standard on said base, a yarn tension weight mounted to slide freely between predetermined limits on said stand- 110 ard, a connecting link extending from the opposite end of said pawl to engage said standard at a point above said weight whereby when more yarn is required said weight is caused to engage and lift said link to rock the pawl and simultaneously lift the package and so assist in withdrawing the pawl there- 115 from to let off more yarn.

In testimony whereof I affix my signature.

GEORGE F. McCAYEY.
